Primary Examiner—Melody N. Brown(74) *Attorney, Agent, or Firm*—Brian J. Rees; Price Heneveld Cooper DeWitt & Litton(57) **CLAIM**

The ornamental design for a mirror, as shown and described.

DESCRIPTION

FIG. 1 is a front view of another mirror construction showing our new design;

FIG. 2 is a top view of the mirror construction shown in FIG. 1; and,

FIG. 3 is a left side view of the mirror construction shown in FIG. 1, the right side being a mirror image thereof. The broken lines in FIGS. 1-3 are provided to show the environment of the present mirror construction design, but do not form a part of the design being claimed.
